CLAIM

I claim the ornamental design for faucet, as shown and described.

DESCRIPTION

FIG. 1 is a perspective view of an embodiment of a faucet. FIG. 2 is a front elevation view thereof.

FIG. 3 is a right side view thereof.

FIG. 4 is a back view thereof.

FIG. 5 is a bottom view thereof.

FIG. 6 is a left side view thereof; and,

FIG. 7 is a top view thereof.

The broken lines showing the bottom surfaces are included for the purpose of illustrating portions of the faucet according to the embodiments that form no part of the claimed design.

1 Claim, 7 Drawing Sheets
